UNITED STATES PATENT OFFICE.

WALTER H. HART, OF NEW BRITAIN, CONNECTICUT, ASSIGNOR TO STANLEY WORKS,
OF NEW BRITAIN, CONNECTICUT, A CORPORATION OF CONNECTICUT.

DESIGN FOR A HINGE-LEAF.

41,306.

Specification for Design.

Patented Apr. 11, 1911.

Application filed January 26, 1910. Serial No. 540,284. Term of patent 14 years.

To all whom it may concern:

Be it known that I, WALTER H. HART, a citizen of the United States, residing at New Britain, county of Hartford, State of Connecticut, have invented a new, original, and ornamental Design for Hinge-Leaves, as herein set forth.

In the accompanying drawing I have shown a plan view of a hinge leaf illustrating my new design.

I claim—

The ornamental design for a hinge leaf, as shown.

WALTER H. HART.
